METHOD OF AND APPARATUS FOR PLACING
PAVEMENT SLABS AND THE LIKE

Corwill Jackson, Ludington, Mich.

Application July 23, 1941, Serial No. 403,667

8 Claims. (Cl. 94—24)

This invention relates to improvements in method of and apparatus for placing pavement slabs and the like.

The main object of this invention is to provide a method of placing highway or pavement slabs which enables the rapid placement of harsh mixtures of concrete or mixtures having no-slump water content or mixtures being of such low water content as to be difficult to spread and to place in a satisfactory manner.

In the accompanying drawing, I illustrate an apparatus by means of which my method may be practiced and illustrating the steps thereof, parts of the apparatus being shown in conventional form.

In the accompanying drawing, 1 represents a side form, 2 the concrete mixture to be treated by the method and 3 the concrete after treatment in accordance with the method.

The apparatus illustrated comprises a carriage designated generally by the numeral 31 having carrying and driving wheels 4 adapted to travel on the forms 1 which constitute tracks or rails, only one form being illustrated. The engine, indicated conventionally at 5, is commonly adapted to drive the carriage as well as to furnish power for the screed constituting a part of the apparatus illustrated.

The screed 6 is of the type adapted to be reciprocated transversely of the path of forward travel, being driven from the crank 7 connected to the screed by the pitman or connecting rod 8. The means for advancing the screed are not illustrated.

The screed is provided with a vibrating unit 9 preferably in the form of an electric motor having a rotor with an unbalancing weight indicated by dotted lines at 10.

At the forward end of the carriage, I provide a spiral or screw type of spreader 11 which is designed to be reversely driven, the spreader being carried by the hangers 12 pivoted at 13 and vertically adjusted by means of the screw 14 having a nut 15 associated therewith and provided with a hand wheel. The spreader is driven from an engine 16 through suitable driving connections indicated generally by the numeral 17 designed to reversibly drive the spreader. The reversible transmission and the means for manually controlling therefor are not illustrated.

At the rear of the spreader is a vibratory member 18, this being of substantial width and adapted to support a substantial mass of material treated or being placed while it is acted upon by the spreader. This vibratory member is sup-

ported by the flexible hangers 19 carried by arms 20 on the rock shaft 21, this rockshaft being provided with an arm 22 having a nut 23 journaled thereon to coact with the screw 24 provided with a hand wheel 25 so that the vibratory member may be raised and lowered, the vibratory member acting as a combined vibrator and strike-off.

The vibratory member 18 is provided with a vibrating motor 26 having a rotor 27 which is provided with an unbalanced weight 28 so that the vibratory member is vibrated at high frequency. This vibratory member acts upon the material while it is acted upon by the spreader to render the same fluid or semi-fluid and thereby facilitate the spreading and placement thereof.

While the material is still in its fluid or semi-fluid condition resulting from such spreading and vibrating treatment, it is subject to the combined action of the screed and of the vibratory strike-off member 29 disposed in front of the screed and in such relation thereto as to provide a narrow reservoir 30 between the face of the screed and the vibratory member 29. The vibratory member is provided with a vibrating unit 31 preferably of the same character as the vibratory units 29 and 26 comprising an electric motor, the rotor 32 of which is provided with an unbalancing weight. The vibratory member 29 is supported for vertical adjustment by the hangers 33.

As the machine is advanced, the reservoir space 30 accumulates a quantity of the treated material indicated at 34, this commonly being the "fines" of the material which builds up therein to such an extent that it is gradually fed down to the screed, insuring a highly desirable surface well supplied with "mortar."

The vibratory member 29 is adapted to support a substantial mass of material as it is advanced; it being advanced at high frequency serves to supplement the vibratory member 18 in reducing the material to the desired condition 45 for most effective screeding and placement, eliminating voids and providing a very compact placement thereof.

By this method, the concrete may be dumped between the forms in which condition it has a high percentage of voids, and as the method is designed for placement of harsh or concrete mixtures or mixtures of low water content it is very difficult to propel either manually or mechanically. However, by subjecting it to the vibrations during the spreading operation, the voids

are very rapidly reduced and the material in which the spreader operates becomes workable and fluid-like. This operation in itself deposits the concrete in a state of high density and with relatively few voids. By vibrating the mixture during this spreading operation, the spreading is accelerated which I have demonstrated increases the spreading capacity in the neighborhood of fifty percent. The material is struck off properly to be acted upon in the succeeding step where it is subjected to the combined action of the second vibrator and screed. The second vibrator acts as a still further vibrator and also acts with the screed to provide the reservoir of surfacing material which is uniformly fed to the screed as is required in order to provide the desirable surface. The resulting placed concrete is very dense and compact and requires but a minimum of time before it may be walked upon or even a truck may be driven thereon without appreciable damage. It is of course preferable that the concrete set before it is open to traffic. By my method, the speed with which concrete may be placed is very greatly increased with resulting economy and practically no manual labor is required in the spreading.

Having thus described my invention, what I claim as new and desire to secure by Letters Patent is:

1. The method of placing concrete mixtures of low water content in pavements and the like, comprising the steps performed successively and continuously of vibrating at high frequency a mass of material to be placed while spreading the material in the zone of vibration thereof transversely of the path of the surface to be paved, thereafter striking off the thus placed material rearwardly of said zone while again vibrating said material adjacent the strike-off zone at high frequency, immediately thereafter screeding the surface thus laid while accumulating a quantity of the last vibrated material in a fluid-like consistency in a space intermediate the screeding zone and said strike-off zone of vibration, and advancing said accumulated material while screeding, whereby the same is gradually fed downwardly by hydrostatic head in advance of the screeding zone.

2. The method of placing concrete mixtures of low water content in pavements and the like, comprising the steps performed successively and continuously of vibrating at high frequency and forwardly distributing a mass of material to be placed, thereafter striking off the thus distributed material rearwardly of said vibration zone while vibrating at high frequency adjacent the strike-off zone, immediately thereafter screeding the surface thus laid while accumulating a quantity of the last vibrated material in a fluid-like consistency in a space intermediate the screeding zone and said vibratory strike-off zone, and advancing said accumulated material while screeding, whereby the same is gradually fed downwardly by hydrostatic head in advance of the screeding zone.

3. The method of placing concrete mixtures of low water content in pavements and the like, comprising the steps performed successively and continuously of rearwardly supporting and vibrating at high frequency a mass of material to be placed while spreading the material transversely in the zone of vibration thereof, screeding the surface thus laid while accumulating a quantity of the material in a fluid-like consistency in a space intermediate the screeding zone

and said zone of vibration, and advancing said accumulated material, whereby the same is gradually fed downwardly by hydrostatic head in advance of the screeding zone.

5. The method of placing concrete mixtures of low water content in pavements and the like, comprising the steps performed successively and continuously of supporting a mass of material to be placed while vibrating said mass at high frequency, thereafter striking off the material rearwardly of said vibration zone while likewise vibrating at high frequency at the strike-off zone, thereafter screeding the surface thus laid while accumulating and advancing a quantity of the last vibrated material in a fluid-like consistency in a space intermediate the screeding zone and said strike-off zone, whereby the same is gradually fed downwardly by hydrostatic head in advance of the screeding zone.

5. An apparatus for placing low water content concrete mixtures in pavements and the like, comprising a forwardly advanceable carriage, a vibratory member extending transverse the carriage and the path of advancement thereof, said vibratory member being engageable with a mass of concrete to be laid, means for vibrating said member at high frequency, a spreader disposed in advance of said vibratory member for spreading engagement in the mass of material vibrated by the latter in the zone of vibration of said mass, a vibratory strike-off member positioned rearwardly of said first named member, means for vibrating said vibratory strike-off member, and a screed disposed immediately to the rear of said vibratory strike-off member to provide a narrow reservoir or hopper therebetween, said vibratory strike-off member vibrating a quantity of the material previously distributed by said first member and spreader and said reservoir accumulating a mass of fines of said material in a semi-fluid consistency adapted to flow downwardly from the reservoir in advance of the screed, said spreader, vibratory members and screed being supported on said carriage for advancement therewith in the aforesaid relation to one another.

6. An apparatus for placing low water content concrete mixtures in pavements and the like, comprising a forwardly advanceable carriage, a vibratory strike-off member extending transverse the carriage and the path of advancement thereof, said vibratory member being engageable with a mass of concrete to be laid, means for vibrating said member at high frequency, a spreader disposed in advance of said vibratory member for spreading engagement in the mass of material, and a screed disposed immediately to the rear of said vibratory member to provide a narrow reservoir or hopper therebetween, said vibratory member vibrating a quantity of the material previously distributed by said spreader and said reservoir accumulating a mass of fines of said material in a semi-fluid consistency adapted to flow downwardly from the reservoir in advance of the screed, said spreader, vibratory member and screed being supported on said carriage for advancement therewith in the aforesaid relation to one another.

7. An apparatus for placing low water content concrete mixtures in pavements and the like comprising a carriage, a vibratory member extending transversely of the carriage and of the path of advancement thereof for advancement therewith, said vibratory member being adapted

to rearwardly support a substantial mass of concrete mixture in front thereof as the vibratory member is advanced against a mass of concrete mixture, means for vibrating said vibratory member and through it the concrete mixture so supported and for a substantial distance in advance of the vibratory member and rendering it fluid or semi-fluid as the carriage is advanced, and a spreader supported on said carriage in front of said vibratory member for advancement therewith and in the zone of the material supported and vibrated by the vibratory member and rendered fluid by the vibrations thereof for spreading the said vibrated material longitudinally of the vibratory member.

8. An apparatus for placing low water content concrete mixtures in pavements and the like

comprising a carriage, a screed member mounted on and extending transversely of the path of travel of the carriage and adapted to rearwardly support a substantial mass of the concrete mixture in front thereof as the screed member is advanced against the concrete mixture, means for vibrating the concrete mixture so supported and rendering it fluid or semi-fluid in advance of the screed member, and a spreader disposed in 10 advance of the screed member for advancement therewith and in the zone of the concrete mixture supported and vibrated by the screed member which has been rendered fluid or semi-fluid and acting to spread the said vibrated material 15 longitudinally of the screed member for screeding action thereby.

CORWILL JACKSON.
